UNITED STATES PATENT OFFICE.

CLAUDE A. NELSON, OF WILMERDING, PENNSYLVANIA, ASSIGNOR TO THE WESTINGHOUSE AIR BRAKE COMPANY, OF WILMERDING, PENNSYLVANIA, A CORPORATION OF PENNSYLVANIA.

TRAIN-CONTROL DEVICE.

Application filed April 20, 1927. Serial No. 185,160.

This invention relates to automatic train control apparatus and more particularly to that type having means for automatically effecting a brake pipe reduction in two stages.

- 5 In the pending application of Clyde C. Farmer and Thomas H. Thomas, Serial No. 692,970, filed February 15, 1924, means are disclosed for automatically effecting a split or two stage reduction in brake pipe pressure, 10 when the train control apparatus operates to make a brake application on the train in territory governed by a medium speed or low speed signal indication. When the train is 15 operating in territory governed by a high speed signal indication and the train control apparatus operates to make a brake application, the split reduction means is automatically cut out and a continuous full reduction in brake pipe pressure is automatically effected. 20 The split reduction means, above referred to, is controlled by a cut-out portion, having a piston, which in turn is governed by the medium speed application valve in the speed governor. When the speed of the train is 25 below the medium speed limit, and the medium speed valve is closed, fluid under pressure equalizes on the opposite sides of the cut-out piston through a port in the piston, and said piston is then held in the split reduction position by a spring, but when the speed of the 30 train is above the medium speed limit and the medium speed valve is opened, the cut-out piston chamber is vented to the atmosphere past the medium speed valve and the split reduction cut-out piston is shifted to the cut-out position. In this position, fluid under pressure continuously flows through the port in the cutout piston and thence to the atmosphere through the opened medium speed 35 valve, so long as the medium speed application valve remains open.

The principal object of my invention is to provide an improved control means for the split reduction cut-out portion of the train control apparatus above referred to, in which, flow of fluid to the atmosphere, when the medium speed valve is opened, is prevented, except when the train control apparatus functions to effect an application of the 40 brakes.

In the accompanying drawing, the single figure is a diagrammatic view of a train control apparatus embodying my invention.

As the construction and operation of this

train control apparatus is substantially the same as that of the pending application, above referred to, the same will not be described in detail herein, but only to the extent deemed necessary to a full understanding of the invention.

The apparatus shown on the drawing includes an application valve device 1, a pilot valve device 2, valve devices 18 and 19 for effecting a brake pipe reduction in two stages, a split reduction cut-out device 4, a speed governor 5 and a plurality of valves adapted to be operated by the speed governor.

The application valve device 1 comprises a casing having a piston chamber 6 containing a piston 7 and a valve chamber 8 containing a slide valve 9, adapted to be operated by said piston.

The pilot valve device 2 comprises a casing having a piston chamber 10, containing a piston 11 and a slide valve chamber 12 containing a slide valve 13, said slide valve having a cavity 14 adapted, in the rearward or release position of the slide valve to connect passage 15 from the application valve piston chamber 6 to passage 16 from the application valve 75 slide valve chamber 8, and in the forward or application position of the slide valve cavity 14 connects passage 15 to an atmospheric exhaust passage 17.

The means for effecting a brake pipe reduction in two stages comprises a control valve device 18, controlled by the fluid vented from the brake pipe in effecting a brake pipe reduction, a hold back valve device 19 and a reduction ensuring valve device 20.

The split reduction cut-out device 4 comprises a casing having a piston chamber 21 containing a piston 22 and a valve chamber 23 containing a slide valve 24, adapted to be operated by said piston. The slide valve 24 has a cavity 25, which, with the piston in the position shown in the drawing, connects passage 26, from the first reduction reservoir 27, to passage 28 from the second reduction reservoir 29. When the cut-out piston 22 and slide valve 24 are in the opposite or downward position, the passages 26 and 28 are disconnected and lapped by the slide valve.

The speed governor 5 is of the usual centrifugal type, adapted to be rotated according to the speed of the train and in operation, is adapted to cause a movement of a push rod 31. Mounted on the outer end of the push rod

is a crosshead 32, carrying a plurality of adjustable tappet stems adapted to operate corresponding valves at various train speeds, including a medium speed application valve 33, which is unseated at and above the medium speed limit. The medium speed valve is contained in a chamber 34 and below the medium speed limit, is seated by the pressure of a spring 35.

10 According to my invention, the piston chamber 21 of the split reduction cut-out device 4 is connected to a passage 36 leading to the seat of the pilot portion slide valve 13, so that when the slide valve is in the usual 15 release position, as shown in the drawing, the passage 36 is lapped by the slide valve, but when the piston 11 and slide valve 13 are shifted to the outer or application position, the passage 36 is connected to the valve chamber 12.

The passage 36 is connected by passage 37, pipe 38, and passage 39 in the speed governor, to chamber 34 containing the medium speed valve 33.

25 In operation, when a train is running above the medium speed limit, the speed governor holds the medium speed valve 33 unseated, so that the medium speed valve chamber 34 and the split reduction cut-out piston chamber 21 are connected to the atmosphere, but normally, there is no venting of fluid to the atmosphere, since the piston chamber 21 is not supplied with fluid under pressure from any source.

30 If a change in signal indication occurs, as from a high speed to a medium or low speed, the pilot valve piston chamber 10 will be vented to the atmosphere, as in the pending application, hereinbefore referred to, so that 35 the pilot valve piston 11 and slide valve 13 are shifted to brake application position, in which the brake application is initiated.

In brake application position, the pilot valve slide valve 13 uncovers the passage 36 and permits fluid under pressure to flow from the valve chamber 12 into passage 36 and then to the split reduction piston chamber 21. Said passage and chamber are vented to the atmosphere through the open medium speed valve in the speed governor, provided the speed of the train exceeds the medium speed limit. The venting of fluid from piston chamber 21 at the medium speed valve 33 is at such a rate that the pressure in said chamber 45 is prevented from being built up by flow from chamber 12, and consequently, the piston 22 and slide valve 24 of the split reduction cut-out device, will not be moved to their inner position against the opposing 50 pressure in valve chamber 23. Thus, above medium speed, the split reduction cut-out device 4 remains in its outer position, as shown in the drawing, in which position, cavity 25 in the slide valve 24 connects the passages 26 55 and 28 from the first and second reduction

reservoirs, respectively, so that a continuous single stage reduction in brake pipe pressure occurs.

If the train is running below the medium speed limit, the speed governor is in such a position, that the medium speed valve 33 is seated by the pressure of the spring 35.

With the medium speed valve seated, if an automatic application of the brakes is initiated, the pilot valve device 2 is shifted to its outer position, as hereinbefore described, and permits fluid under pressure from the valve chamber 12 to flow to passage 36 and to the split reduction cut-out piston chamber 21. Since the medium speed valve 33 is now closed, the chamber 21 and passage 36 are not vented to the atmosphere, and the pressure builds up in piston chamber 4, so that the fluid pressure on the opposite sides of the cut-out piston 22 become equal and the pressure of spring 40 then shifts the piston 22 and slide valve 24 to their upper position, in which the passages 26 and 28 are disconnected, with the result, that the brake pipe pressure is reduced in two stages, in the manner described 85 in detail in the pending application, hereinbefore referred to.

It is evident, that since fluid under pressure is supplied to the split reduction cut-out valve piston chamber 21 only when the apparatus operates to effect an application of the brakes, that while said chamber is open to the atmosphere through the medium speed valve 33, when the speed of the train exceeds the medium speed limit, there will be no flow 100 of fluid under pressure to the atmosphere, while the train is running, unless the apparatus is operating to effect an application of the brakes.

Having now described my invention, what I claim as new and desire to secure by Letters Patent, is:—

1. In a train control apparatus, the combination with means for effecting an application of the brakes in two stages, of a valve device operable by fluid under pressure for rendering said means effective to cause an application of the brakes in two stages, means operable when the speed of the train is above a predetermined speed limit for venting fluid from said valve device, and means operable only upon operation of the apparatus to effect an application of the brakes for supplying fluid under pressure to said valve device.

2. In a train control apparatus, the combination with means for effecting an application of the brakes in two stages, of a valve device operable by variations in fluid pressure for either rendering said means effective or ineffective to cause an application of the brakes in two stages, means operated according to the speed of the train for venting fluid from said valve device, said means operable only in applying the brakes for supplying fluid under pressure to said valve device.

3. In a train control apparatus, the combination with means for effecting an application of the brakes in two stages, of a valve device operable by variations in fluid pressure for either rendering said means effective or ineffective to cause an application of the brakes in two stages, means operated according to the speed of the train and independently of the signal indication for venting fluid from said valve device, and means operable only when the apparatus operates to effect an application of the brakes for supplying fluid under pressure to said valve device.

4. In a train control apparatus, the combination with means for effecting an application of the brakes in two stages, of a valve device subject on one side to fluid under pressure and operated by supplying fluid under pressure to the other side for rendering said means effective to apply the brakes in two stages and operated by venting fluid from said other side for rendering said means ineffective to apply the brakes in two stages, and means operable to initiate an application of the brakes and to supply fluid under pressure to said other side of said valve device.

5. In a train control apparatus, the combination with means for effecting an application of the brakes in two stages, of a valve device operated by variations in fluid pressure for either rendering said means effective or ineffective to cause an application of the brakes in two stages, a speed governor controlled by the speed of the train, a valve operated by said governor when the speed of the train is above a predetermined speed

limit for venting fluid from said valve device and when the speed is below a predetermined speed limit for preventing the venting of fluid from said valve device, and means operated when the brakes are applied for supplying fluid under pressure to said valve device.

6. In a train control apparatus, the combination with an application valve device for initiating an application of the brakes, a pilot valve device for controlling the operation of said application valve device, and means for effecting an application of the brakes in two stages, of a valve device operated by variations in fluid pressure for either rendering said means effective or ineffective to cause an application of the brakes in two stages, said pilot valve device having means for supplying fluid under pressure to said valve device.

7. In a train control apparatus, the combination with an application valve device for initiating an application of the brakes, a pilot valve device for controlling the operation of said application valve device, said means for effecting an application of the brakes in two stages, of a valve device operated by variations in fluid pressure for either rendering said means effective or ineffective to cause an application of the brakes in two stages, said pilot valve being adapted to supply fluid under pressure to said valve device when operated to effect the operation of said application valve device.

In testimony whereof I have hereunto set my hand.

CLAUDE A. NELSON.
